United States Patent Office.

FRANKLIN ROBERTS, OF NEW ORLEANS, LOUISIANA, ASSIGNOR TO NEW ORLEANS PNEUMATIC PROPELLING COMPANY, OF SAME PLACE.

Letters Patent No. 105,128, dated July 5, 1870.

IMPROVEMENT IN TANKS FOR HOLDING COMPRESSED AIR.

The Schedule referred to in these Letters Patent and making part of the same.

I, FRANKLIN ROBERTS, of the city of New Orleans and State of Louisiana, have invented a certain Improvement in Tanks for Holding Compressed Atmospheric Air, when the same is used as the motive power for propelling street-railroad cars, of which the following is a specification.

My invention relates especially to the construction of paper tanks; and

It has for its object—

First, to prevent the saturation of the same with the water or moisture that enters the tank either directly from the compressing-pump or by reason of the condensation resulting from the compression of a large body of air into a small space.

Secondly, to strengthen the tank by means of an outside wrapping of the cord, technically known as "marline," which, at the same time, prevents the tank from flying to pieces in case of an explosion, and hence interposes an effectual guard against injury to any person or thing should an explosion ever take place.

Thirdly, to construct, put in, and secure in their places, the metallic heads which are necessary in the use of paper tanks, as made by me, in such manner that, while no amount of pressure from within can drive them out, the greater that pressure the tighter will be the joints around them; and

Finally, the adaptation of outside bands to the ends of the tanks, and the keeping of such bands in place by means of an outside yoke at each end of the tank, and longitudinal rods outside the tank extending from one end thereof to the other.

But my invention will be more easily and quickly understood if described by direct reference to the accompanying drawing, whereon—

Figure 1 is an end view of a tank with its heads in place, as when ready to be put on a car; and

Figure 2 a longitudinal section, through line *a b* of fig. 1, of a part of a tank and one head thereof.

In the formation of the shell *A* of the tank, a mandrel or "former" is employed in order to cause said shell to assume the shape shown on the drawing; that is to say, to taper for a short space at each end inwardly in a straight line from the points at which a reduction of the diameter commences to the said ends.

The black line *a*, which marks the interior surface of the shell of the tank, represents a wrapping of sheet India rubber, which is put tightly around the "former" before the paper is put on, in such a manner that one edge will overlap the other with the view to cover the joint which would otherwise obtain.

This interior wrapping of sheet rubber effectually prevents the saturation of the enveloping folds of paper by the water or moisture which may find its way into the tank in its actual use, and hence fulfills the purpose of preserving the normal strength of the paper as long as the tank may be used.

The elastic properties of the sheet of rubber will prevent the formation of any wrinkles or pockers on the tapering ends of the "former," and hence secure as much smoothness of surface there as anywhere else in said sheet.

Over the India rubber exterior lining of the tank comes the wrapping of strong paper, well saturated with glue or varnish, the same being wound around spirally, and so as to break the joints everywhere, as one fold after another is put around, until from thirty to sixty folds encircle the rubber according to the thickness and strength of the paper, and the tension of air it is designed to withstand.

Outside the paper I wind on one thickness or layer of the tarred, slightly-twisted cord, technically called "marline," as closely as it can be wrapped, and as tightly as the strength of the marline will permit.

This wrapping of marline adds great strength to the shell without greatly increasing its weight, and, in case of explosion, prevents the tank from flying into fragments.

The "former," which is so constructed as to be susceptible of being reduced in diameter by the withdrawal, endwise, of certain of its parts, is now taken out, leaving the shell of the tank at each of its ends of tapering form, as shown at 1 2, fig. 2.

The ends of the tanks are closed with heads, *B*, which, upon their periphery or rim, have an inclination or bevel from their inner to their outer edges, which corresponds precisely with the inclination or taper of the end of the tanks, as clearly shown at fig. 2.

The diameter of the heads *B* should be such that the shell at the ends of the tank shall extend a little space beyond them when first put in, in order to allow for their gradual movement outwardly under the influence of the enormous pressure which the compressed air develops when the tension thereof approaches three hundred pounds to the square inch, which said tension experience has demonstrated to be requisite in order to make the pneumatic engine an effective motor for the propulsion of street-cars the necessary distance, without replenishing before getting back to the general reservoir.

In order to combine lightness with strength in the heads *B*, the plate *C* (see fig. 1) is made thin, but is strengthened by radiating ribs, *c*, projecting above the surface of the plate, as shown both on the inside and outside thereof, the ribs on the inside being placed exactly between those on the outside, so as to make the reinforcement they impart as extended as possible.

Outside the inclined or tapering ends of the tanks, bands, *D*, encircle the same, as shown at both figures.

These bands, on their internal surfaces, are inclined or beveled in reverse direction thereto, and to the heads *B*, so as to conform precisely to the taper of the ends, as shown at fig. 2. In consequence of this formation

of the bands, the pressure from within the tanks against the heads does not tend to throw the bands off, but, on the contrary, to fix them the more firmly in their places, because the shell of the tank, interposing between the heads and the bands, no movement on the part of the heads can have any effect on the bands, except in the plane of the plate of which the head is composed, which makes the bands gripe the more tightly instead of throwing them off.

The bands D may have three or more lugs, E, projecting beyond their outer surfaces, in which holes are made to receive the ends of small bars of iron, if desired, that extend from one head to another, and, by means of screw taps or keys, hold the two heads in place. But, in addition to this, the heads B are provided with a central screw-bolt, F, in order to hold in position a cross-bar or yoke, G, which, taking against the outer edge of the band, at once affords a means for preventing the same from slipping off, and of tightening the head B. I have found, in fact, that this yoke is usually quite sufficient to hold the bands in place without the aid of the rods to which I have just referred, when the tension was even more than three hundred pounds to the square inch, which is the maximum in the propulsion of city cars by C. W. Wailey's pneumatic engine.

The heads B are inserted into the tanks edgewise, by a gentle compression or flattening of the ends of the latter, so as to make them assume an elliptical form, and then turned into proper position.

They can at any time be taken out in the same way, if, for any cause, it be necessary to withdraw them, as, for example, to empty any water that may have got into the tank, or to dry the interior thereof, &c.

My invention is an improvement on the paper reservoir for compressed air as patented by Charles W. Wailey, September 1, 1868, which experience has proved to be imperfect, while mine, on the contrary, fulfills every condition as to strength, durability, lightness, and cheapness, which is required to make the pneumatic engine a perfect motor for the propulsion of street-cars.

I claim as my invention—

1. A paper tank, of which the ends are inclined or tapering, as herein described, when the same is lined with sheet India rubber, and enveloped with an external layer of marline, as herein described, for the purpose set forth.

2. The head B, when provided with an inclined or beveled periphery, and otherwise constructed as described, in combination with a band, D, a yoke, G, and a screw-bolt, F, when all the parts are used in connection with the tank herein described, for the purpose set forth.

FRANKLIN ROBERTS.
